UNITED STATES PATENT OFFICE.

ELI EPSTEIN, OF LEOMINSTER, MASSACHUSETTS.

CYLINDER-LOCK.

1,230,387.

Specification of Letters Patent. Patented June 19, 1917.

Application filed January 29, 1917. Serial No. 145,044.

To all whom it may concern:

Be it known that I, ELI EPSTEIN, a subject of the Czar of Russia, residing at Leominster, county of Worcester, State of Massachusetts, have invented an Improvement in Cylinder-Locks, of which the following description, in connection with the accompanying drawing, is a specification, like characters on the drawing representing like parts.

10 This invention relates to cylinder locks and has for its principal object to provide a novel lock of this type which is non-pickable, and for other objects to provide the further improvements in cylinder locks

15 which are hereinafter set forth.

One way in which some cylinder locks can be picked is by inserting a thin ribbon-like wire between the plug and the casing and at the same time manipulating each tumbler pin separately by means of a skeleton key so as to bring the joint between the sections of each pin into alinement with the periphery of the barrel, and as each pin is thus lined up, working the wire ribbon in between the sections of the pin, thus holding them in this position. When the tumbler pins have thus all been lined up and are held in this position by the lock-picking implement, the plug can be turned, thereby opening the lock. Another way in which cylinder locks are sometimes picked is by placing a slight pressure on the end of the plug and at the same time giving the lock a series of hammer-like blows. Such blows tend to cause 25 the tumbler pins to jump in their sockets, and by skilfully applying the proper pressure to the end of the plug while such blows are applied, the pin sections in the casing can be prevented from moving downwardly 30 under the influence of the springs, but will be permitted to move backwardly by the tapping action of the pin sections in the plug due to such blows until all the pins are lined up. When this has been successfully 35 accomplished, the plug may be turned, thus opening the lock.

As stated above, the principal object of my present invention is to provide an improved cylinder lock which cannot be picked in either of these ways, or in any other known way. I accomplish this object by connecting the sections of the end tumbler pins in such a way as to permit the lock to be manipulated as usual by the insertion of 50 the proper key, but to prevent the sections of the tumbler pins from being separated

and held in their lined-up position by the insertion of any lock-picking implement, such as above described. The manner of connecting the sections of the tumbler pins 60 also prevents the lock from being picked by the jarring operation above referred to.

In order to give an understanding of my invention, I have illustrated in the drawings, a selected embodiment thereof which 65 will now be described, after which the novel features will be pointed out in the appended claims.

In the drawings, Figure 1 is a perspective view of a cylinder lock embodying my invention;

Fig. 2 is a longitudinal sectional view on the line 2—2, Fig. 1;

Fig. 3 is a section on the line 3—3, Fig. 2;

Fig. 4 is a section on the line 4—4, Fig. 2;

Fig. 5 is a perspective view of the comb-like pin-positioning member;

Fig. 6 is a perspective view of one of the tumbler pins showing the sections connected;

Fig. 7 is a perspective view of one of the sections of a tumbler pin;

Fig. 8 is a perspective view of the plug.

Figs. 9 and 10 are views of two different keys that may be used for opening my improved lock.

1 indicates the casing of the cylinder lock which is provided with the usual bore in which is received for rotative movement the usual plug 2 having its key-hole slot 3. The 90 plug is also provided with the pockets 4 to receive portions of the tumbler pins, and the casing is provided with other pockets or spaces 5 in which the tumbler pins are partially received, the pockets 4 and spaces 95 5 being normally in alinement to receive the tumbler pins. The tumbler pins are formed in a plurality of sections, and each tumbler pin is backed by a spring 6, as usual in cylinder locks. In my improvement, 100 however, the sections of some at least of the tumbler pins are connected together so as to prevent them from being separated longitudinally by any lock-picking process. The connection between the sections of the 105 tumbler pins, however, is such as to permit the plug to be turned for opening the lock whenever the tumbler pins are properly lined up. The tumbler pins may be made in two or more sections as desired. I have 110 herein illustrated each tumbler pin as comprising the two sections 7 and 8, the section

8 being received in the pockets 4 formed in the plug, and the section 7 being received in the spaces 5 formed in the casing. The sections of the two end pins at least, and if desired the sections of all the other pins, are connected in the manner best seen in Figs. 6 and 7. Each pin section 8 is formed at its end with a lip 9 and groove 10, and the section 7 is provided with a lip 11 adapted to enter the groove 10 and with a groove 12 to receive the lip 9. The sections 7 and 8 are thus connected together so that they cannot be separated in the direction of their length, so long as these lips and grooves have their interlocking engagement. The pin at the left-hand end of the lock is so disposed that the lip 11 on the upper section 7 extends toward the right-hand end of the lock and the lips and grooves on the pin at the right-hand end of the lock are so disposed that the lip 11 of the upper section 7 extends toward the left-hand end of the lock. The barrel 2 is provided with grooves 13 which intersect the pockets 4 therein, as best seen in Fig. 8.

The tumbler pins intermediate the end pins will preferably have the same tongue-and-groove connection between the sections thereof as above referred to, although this is not essential.

When the key is inserted in the key-hole slot, the tumbler pins are lined up so that the upper edge of the lip 9 of each lower pin section comes into line with the peripheral surface of the plug 3, and the lower end or surface of each lip 11 on the upper pin section comes in line with the bottom of the grooves 13. The pins are held from turning movement so that the lips are always directed toward the ends of the plug. With this arrangement, it will be seen that when the pins are properly lined up by the insertion of the key, the plug can be turned to open the lock as the lips and grooves will merely be withdrawn sidewise from each other. When the plug is returned to locking position, the lips and grooves of the pins will move back into their interlocking engagement.

With this construction, it is not possible to pick the lock by the insertion of a thin ribbon-like lock-picking implement between the plug and the casing because in each of the end pins the joint between the end of the lip 11 on the upper pin section 7 and the bottom of the groove 10 on the lower pin section 8 is situated in the groove 13 and below the periphery of the plug 2, thus making it impossible to insert a lock-picking implement between the sections of the end pins.

In order that the lock may operate properly, it is essential that the tumbler pins should be held from turning movement, and I propose to secure this end by making

the pins non-circular in cross section and by making the pockets for the pins of corresponding shape. I have herein illustrated each pin as rectangular in cross-section, although the pins might have any suitable non-circular cross-sectional shape. In order to provide in an inexpensive manner the proper-shaped spaces 5 in the casing for the pins, I make the casing with a longitudinally-extending groove 14 having a width equal to one transverse dimension of the pins, and then place in said groove a comb-like pin-positioning member 15 which is slotted to form the spaces 5. This pin-positioning member 15 thus provides the proper-shaped spaces 5 for the pin sections 7. The pockets 4 in the plug 2 will also have a proper cross-sectional shape to fit the pin sections 8. The groove 14 in which the pin-positioning member 15 is received extends through the rear end of the casing 1, thus permitting said member 15 to be inserted into the groove through the end of the casing. After said member is in place, the member 15 is of such a length that when in position it terminates short of the end of the casing, and a closing strip 16 is secured in the end of the groove 14 thereby locking the member 15 in place. This construction whereby some at least of the pins have their sections connected also prevents the possibility of picking the lock by the jarring process above referred to because when the pins are jarred out of position by a blow received by the casing, both sections of each pin will move together and the pins cannot be lined up by a tapping of one section of the pin against the other due to repeated blows given to the lock.

The combination can be changed with my improved lock in usual manner by first using the proper key to partially turn the plug 2 and then removing said plug and replacing the pin sections therein with other pin sections of different lengths.

I have herein illustrated each of the pin sections 8 as cut away or rabbeted at its lower edge to form a shoulder 17, and the different pin sections 8 are so formed that the shoulders 17 thereof come at different distances from the lower ends 18, the shoulders on some pin sections being nearer the end 18 than on other pin sections. The key-hole slot is made relatively wide at its upper end, as shown at 19. The purpose of this construction is to permit the lock to be opened by two different keys having different widths at their operative edges. If, for instance, a key, such as shown in Fig. 9 is used which is relatively wide at its serrated or operative edge 20, then when this key is inserted in the key-hole slot, it will engage the lower ends 18 of the pins, and said pins will be lined up by their lower ends. If, however, a key such as shown in Fig. 10 is

used which has a comparatively-narrow serrated or operative edge 21 which is shaped so that it will engage the shoulders 17 of the pin sections 8, then said pin sections will be lined up by the shoulders 17. As these shoulders are situated at different distances from the ends 18 of the pins, the key which coöperates with the shoulder 17 will have a different shape from that which is shown in Fig. 9 and which coöperates with the ends 18. One of these keys may be in the nature of a master key and the other in the nature of a working key.

I claim:

15. 1. In a cylinder lock, the combination with a casing, of a plug rotatably mounted therein, said plug and casing having tumbler-pin-receiving pockets, and tumbler pins in said pockets, each pin comprising a plurality of sections and some at least of the pins having their sections connected.
20. 2. In a cylinder lock, the combination with a casing, of a plug rotatably mounted therein, said plug and casing having tumbler-pin-receiving pockets, and tumbler pins in said pockets, each pin comprising two sections and some at least of the pins having their sections connected.
25. 3. In a cylinder lock, the combination with a casing, of a plug rotatably mounted therein, said plug and casing having tumbler-pin-receiving pockets, and tumbler pins in said pockets, each pin comprising a plurality of sections, and the end pins having their sections connected.
30. 4. In a cylinder lock, the combination with a casing, of a plug rotatably mounted

therein, said plug and casing having tumbler-pin-receiving pockets, and sectional tumbler pins in said pockets, each section 40 of some at least of said pins having a lip which is received in a groove in the corresponding section.

5. In a cylinder lock, the combination with a casing, of a plug rotatably mounted 45 therein, said plug and casing having tumbler-pin-receiving pockets, and sectional tumbler pins in said pockets, one section of each pin having a lip extending toward the end of the plug which is received in a groove 50 in the corresponding pin section.

6. In a cylinder lock, the combination with a casing, of a plug rotatably mounted therein, said plug and casing having tumbler-pin-receiving pockets, and sectional 55 tumbler pins in said pockets, one section of each pin having a lip extending toward the end of the plug which is received in a groove in the corresponding pin section and the plug having grooves 13 in alinement 60 with the pins.

7. In a cylinder lock, the combination with a casing, of a plug rotatably mounted therein, said plug and casing having tumbler-pin-receiving pockets, sectional tumbler 65 pins in said pockets, one section of each pin having a lip extending toward the end of the plug which is received in a groove in the corresponding pin section, and means for preventing the tumbler pins from turning 70 movement in their pockets.

In testimony whereof, I have signed my name to this specification.

ELI EPSTEIN.
